DISAPPEARING DOOR HANDLE

Earl C. Akers, Detroit, Mich.

Application December 28, 1933, Serial No. 704,358

17 Claims. (Cl. 70—208)

This invention relates to a door lock, and more particularly to a door lock having a disappearing handle and especially adapted for use upon the door of an automobile.

Stream lining of automobile bodies is now in vogue and any projection of any part is not looked upon with favor as it destroys the stream line effect, and it is therefore most desirable to provide a lock having a handle adapted to be retracted into a recess in the door, to lie flush with the surface of the door, thus completing the stream line effect and providing a door having no projections upon which a person entering or leaving the car is liable to catch his clothing. Further, a projecting handle is undesirable, as it offers a place for the engagement of a tool or other instrument by means of which the lock may be broken or the handle twisted off when locked.

An object of the present invention is to provide a suitable disappearing or retractable handle for door locks or catches especially constructed and arranged for application to doors of automobile bodies, and to provide an arrangement whereby the handle will be automatically projected upon the unlocking of a separate key operated lock for holding said handle in retracted position, said separate lock being arranged to automatically lock and hold said handle when the same is fully retracted.

A further object is to provide an arrangement whereby the latch bolt of the door lock may be operated by either the outside retractable handle or by an inside handle, and said latch bolt will be operated to latch the door in closed position, by the closing of the door with the handles in any position, without effecting an operation of said handles. It is also an object to provide an arrangement whereby a release of the outside handle may be effected by an operation of the inside handle which is then operative to unlatch the door, and whereby the outside handle may be retracted by the turning of the inside handle, and to provide a simple construction and compact arrangement which may be readily mounted within an automobile door of the usual construction having a sliding glass window, and which construction and arrangement embodies certain other new and useful features, all as hereinafter more fully described and shown in the accompanying drawing, in which—

Figure 1 is a transverse vertical section through a door and showing a lock mechanism illustrative of an embodiment of the present invention, mounted therein;

Fig. 2 is a horizontal section substantially upon the line 2—2 of Fig. 1;

Fig. 3 is a vertical section substantially upon the line 3—3 of Fig. 1; and

Fig. 4 is a similar sectional detail upon the line 4—4 of Fig. 1.

A hollow door of the usual or any suitable construction is formed of sheet metal with an outer side wall 1, an inner side wall 2, and a connecting edge wall 3. Within the front wall is a slot with a plate 4 formed with a like slot, secured upon its outer face and a similar plate 5 secured upon its inner face, these plates being firmly riveted, bolted or otherwise secured in place by any suitable means, such as bolts or rivets having plain heads countersunk in said outer plate so that said plate cannot be removed from the outside, this slotted wall and plates together providing a vertically elongated opening or slot 6 within which a handle member 7 fits, the body of said handle being shaped to completely fill this slot when said handle, which is pivotally supported adjacent its upper end at 8 upon inwardly extending ears on the plate 5, is swung inwardly to retracted position, in which position the outer surface of said handle lies flush with the outer surface of said outer plate 4. Upon the lower end of this handle is a laterally projecting and curved grip portion 9 to afford a better hold for the hand of the operator when said handle is swung outwardly to projected position by a suitable spring 10 which, as shown, may be in the form of a flat spring attached at one end to the outer wall of the door as at 11 with its free end resting against the inner end of the grip portion and projecting laterally from the pivoted end of the handle, is an ear 12, and intermediate the ends of said handle, is a stop member projecting over the handle to form a stop to limit the inward swing of the handle against the action of said spring.

To lock said handle 7 in retracted position and hold it in that position against the action of said spring 10, a notch 13 is formed in the lower end surface of said handle to be engaged by the upwardly projecting end of a dog 14 pivoted at 15 to the plate 5 laterally of the lower end of the slot 6 and normally held by a spring 16 in contact with a stop 17 with its projecting end in the path of said handle so that when said handle is swung inwardly to fully retracted position, said end of said dog will engage in said notch 13 and lock the handle retracted. As illustrative of one means for releasing, from outside the door, said dog from engagement with said

handle, to release the handle and permit its spring 10 to swing the same outwardly to a position where it may be conveniently grasped by the hand of the operator, any suitable key operated lock mechanism may be provided, and as illustrative of such mechanism, a rocker 18 is shown as pivotally supported intermediate its ends with its upper end portion loosely connected to said dog 14 and its lower end portion extended alongside a key hole 19 in the wall 1 and plates 4 and 5, so that by inserting a suitably shaped key from outside the door and then turning the key, the rocker 18 will be rocked and swing the dog 14 downwardly against the action 15 of its spring 16, disengaging it from the notch 13 in the handle 9 and permitting the spring 10 to swing said handle outwardly.

To normally hold the door in closed position, the usual latch bolt 20 is mounted in a guide 20 way on the inner wall 2 of the door and a spring 21 is arranged in the usual way to yieldingly hold said latch bolt in projected position to engage a strike plate (not shown) on the door jamb. Mounted within suitable bearings within the 25 door and extending horizontally inward through the inner wall 2 and below and adjacent the lower side of the latch bolt 20, is a shaft 22 upon the outer end of which shaft at the inner side of the door, is secured an inside handle 23 for operating the latch mechanism from inside 30 the car. Mounted upon this shaft below said latch bolt for free turning movement thereon, is a latch bolt operating disk 24 having a radially projecting lug 25 to engage at one side 35 only a shoulder on the lower side of said latch bolt and a laterally projecting pin 26 is provided on said disk to engage within an elongated notch 27 in the periphery of a collar 28 secured to said shaft 22 adjacent said disk 24. A coiled spring 40 28a may, as shown, be provided and is made fast at one end to any convenient fixed part of the door and at its opposite end to a peripheral pin on the collar 28 to turn said shaft 22 and handle 23, said spring being of just sufficient strength 45 to support said handle in a horizontal position against its tendency to turn downwardly, thus preventing undue vibration and rattling when the parts are in the position shown in Fig. 1, or this spring may be omitted, as it performs no 50 function in the operation of the mechanism.

On the extreme inner end of the shaft 22, is secured a head 29 having arms projecting laterally in opposite directions radially of said shaft and normally in a plane extending approximately at 45° to the horizontal, and projecting from the outer end of one of said arms is a pin 30 extending parallel with the axis of said shaft at one side thereof and to the outer end of the other arm, is pivotally attached at the opposite 55 side of said shaft, a link 31 having a limited sliding connection with one end of a rocker bar 32 by means of a stud on said bar passing through a longitudinal slot 33 in the upper end of said link 31, said rocker being pivotally supported intermediate its ends upon a suitable bracket 34 secured to the inner wall 2 and end wall 3 of the door and which bracket also forms a guide for the latch bolt 20 and is formed with a bearing for the inner end of the shaft 22, said rocker 60 bar 32 being thus supported at a considerable distance above the head 29 and also the upper or pivoted end of the handle 7. To the end of said rocker opposite that to which the link 31 is connected, is pivotally attached the upper 65 end of a link 35, the lower forked end of which

link is pivotally attached to the laterally projecting ear 12 on the pivoted end of said handle 7. Pivotally supported intermediate its ends, as at 37 is a throw-out lever 38 having a laterally extending lip 39 adapted to be engaged by the 5 pin 30 on the head 29 upon rotation of the shaft 22, and this throw-out lever has a stud 40 at its lower end to engage a longitudinal slot in an arm 41 of the dog 14 extending upwardly from the pivoted end of said dog. Therefore upon 10 rotation of the shaft 22 and head 29 in the proper direction by the inside handle 23, the pin 30 on said head will come in contact with the lip 39 on the upper end of the throw-out lever 38, rocking said lever and through its connection 15 with the dog 14, swing the same to disengage it from the notch 13 in the handle 7 and thus release said handle so that said handle will be swung outwardly or projected by its spring 10.

When said handle 7 has been so released by 20 the locking dog 14 and swung outwardly by its spring 10, the person outside the car may grasp said handle 7 and by swinging it further, create a downward pull upon the link 35 which in turn will rock the bar 32, which, after a certain 25 amount of swing has taken place due to the slot 33, will finally create a pull upon the link 31 which will rotate the head 29, shaft 22, collar 28 and handle 23 and after this rotation of said collar has turned the same sufficiently to bring 30 the upper end of its notch 27 into contact with the pin 26, the disk 24 will be rotated and through the engagement of its lug 25 with the shoulder on the latch bar 20, will retract said latch bar and unlatch the door, so that this person may 35 open the door and enter the car. Immediately upon his release of the handle 7, the spring 21 will act to again project the latch bolt, this movement of said bolt acting through the engagement of its shoulder with said lug 25, to 40 turn said disk 24 and, through the engagement of said pin 26 thereon with the upper end of said notch 27 in said collar 28, to turn said collar and consequently said shaft 22 back to normal position as shown in Fig. 4, in which position the door may be slammed shut, retracting the latch bolt by its coming into contact with its latch plate, without affecting the position of any of the other parts, as the latch is free to move inwardly against the action of its spring 50 21, its shoulder moving away from said lug 25.

Upon entering the car this person may therefore slam the door shut, the latch bar being retracted against the action of its spring 21 by striking the latch plate, and if he wishes to 55 then lock the door to prevent its being opened from the outside, as by some holdup robber, it is only necessary for him to turn the inside handle 23 from neutral or horizontal position in a clockwise direction, such direction of movement of said handle being permitted as the disk 24 is free to be rotated in that direction, due to the fact that its lug 25 moves away from the shoulder on the latch bar 20 but when said disk is rotated through the turning of the shaft 22 by 60 such movement of the inside handle, the collar 28 turning with said shaft and the lower end of its notch 27 being thereby brought into engagement with said pin 26 on said disk, the head 29 turning with said shaft, thus exerting a downward pull on the link 31, and as the handle 7 is in projected position at this time, the stud on the rocker 32 is in contact with the upper end of the slot in 31, and this engagement of said stud on the rocker 32 engages the upper 70 75

end of the slot 33, will rock the rocker, exerting an upward pull on the link 35 which will swing the handle 7 inwardly against the action of its spring 19, until the dog 14 of the key operated lock engages in the notch 13 of said handle, locking the door with the handle in position flush with the outer surface of the door.

The lost motion between the link 31 and rocker 32 permits of first, unlocking the outside handle by turning the inside handle 23 in a counterclockwise direction sufficiently to bring the pin 39 into contact with the lever 38 and release the dog 14 from the handle 7 and then by a continued rotation of said inside handle, the door 15 may be unlatched.

If found desirable the key operated lock for the handle 7 may be omitted from the locks of all but one of the doors of the car and the spring actuated catch or dog 14 alone employed 20 to lock said handle in retracted position, so that it will be necessary to operate such lock or locks by means of the inside handle to release the outside handle and unlock such door or doors, and any door not provided with a key lock may be 25 quickly locked from outside the car, by simply pushing the outside handle to retracted position. A person within the car may thus lock or unlock any one or all of the doors at any time by a manipulation of the inside handle of each lock, 30 but with all doors locked, a person outside the car can open only the door provided with the key operated lock and when so locked the outside handles of all doors will be in retracted position with the outer surface of each lying flush 35 with the outer surface of the door, thus eliminating all projections to which some sort of a tool might be applied to break the lock. Therefore the person within the car may protect himself against desperados by locking all doors, which 40 is not possible with the usual equipment where the door may be locked or unlocked from outside the car only.

The specific construction and arrangement of connecting means between the inside and outside 45 handles, and between said handles and latch bolt and outside handle releasing means, may be varied to suit the particular conditions of installation, the construction shown being employed where the space is very limited, due particularly to the guide way 42 for the vertically 50 slideable glass panel or window 43 usually employed in automobile body doors, but it will be understood that this mechanism may be modified within the scope of the appended claims as 55 well as the form and arrangement of the outside handle and recess therefor in the outer wall of the door, without departing from the spirit of my invention and I do not, therefore, limit myself to the particular construction shown.

60 Having thus fully described my invention, what I claim is:

1. The combination with a door having a recess in its outer side; a lock for said door having an outside handle projectable from and retractable into said recess, a spring exerting a constant force tending to project said handle from said recess, means for releasably holding said handle in retracted position within said recess against the action of said spring, a latch bolt for holding said door in closed position, an inside handle, and means connecting said handles to be operated thereby and operative to release said holding means, retract said outside handle, and operate said latch bolt, said outside handle 65 being projected by said spring when released by

said holding means independently of said connecting means.

2. A door lock including an outside handle pivotally supported for swinging movement into and out of a recess in the outer side of a door to which said lock is applied, a spring exerting a force tending to project said handle, means for releasably holding said handle retracted within said recess, a latch bolt for holding said door in closed position, an inside handle, means for releasing said holding means, and means operatively connected to both of said handles for retracting said outside handle and for operating said bolt to release said door and for releasing said holding means by operation of said inside handle, said means connecting said handles embodying lost motion to permit projection of said outside handle by said spring independently of said means.

3. A door lock including an outside handle pivotally supported for swinging movement into and out of a recess in the outer side of a door, yieldable means normally tending to swing said handle outwardly, an inside handle at the inner side of said door, a shaft upon the outer end of which said inside handle is secured, a latch bolt for holding the door in closed position, a spring to normally hold said bolt projected, means operatively connecting said shaft and bolt for retracting said bolt by rotation of said shaft, and means connecting the inner end of said shaft and said outer handle for transmitting motion from said shaft to swing said handle and to rotate said shaft by a swinging movement of said handle.

4. A door lock including an outside handle pivotally supported for swinging movement into and out of a recess in the outer side of a door, means for releasably holding said handle in retracted position within said recess with the outer side of said handle lying flush with the outer surface of the door, a latch bolt for holding the door closed, an inside handle at the inner side of the door, a shaft upon which said inside handle is secured, means on said shaft for operating said bolt, and means on the inner end of said shaft for operating said holding means to release said outside handle and permit the same to swing outwardly.

5. In a door lock as characterized in claim 3, and wherein said means connecting the inner end of said shaft and outer handle comprises a head on the inner end of said shaft and a link connection between said head and said outer handle, said link connection embodying lost motion, between certain of said links, whereby said inside handle may be rotated to operate said latch bolt without operating said outside handle.

6. A door lock as characterized by claim 4, and wherein said means on the inner end of said shaft for operating said holding means comprises a head and wherein said holding means for said outside handle includes a dog to engage a notch in said handle and a lever operatively connected to said dog and positioned to be engaged by a pin on said head to operate said lever and release said dog when said shaft and head are rotated.

7. A door lock as characterized in claim 4, and wherein said means on the inner end of said shaft for operating said holding means is arranged to release said holding means in timed relation to the operation of said latch bolt and the unlatching of the door, whereby said outside handle is first released and projected and then

the latch bolt is operated by the turning of said inside handle and shaft.

8. In a door lock the combination of an outside handle pivotally supported for swinging movement into and out of a recess in the outer side of the door, an inside handle, a shaft upon which said inside handle is secured, a spring projected latch bolt, means for retracting said latch bolt against the action of this spring, means on said shaft for operating said means for retracting said latch bolt and affording lost motion connection therewith, a head on the inner end of said shaft, a rocker, links connecting the ends of said rocker with said head and outside handle respectively, one of said links having a lost motion connection with said rocker, a pin on said head projecting therefrom, means for locking said outside handle in retracted position, said means including a dog to engage a notch in said handle and a lever operatively connected at one end to said dog with its opposite end positioned to be engaged by said pin upon rotation of said head and shaft, and a spring normally operative to project said outside handle.

25 9. A door lock including a handle pivotally supported for swinging movement into and out of a recess in one side of a door, yieldable means normally tending to project said handle from said recess, locking means for locking said handle within said recess against the action of said yieldable means, a second handle, and means operated by said second handle to operate said locking means and release said first named handle for projection by said yieldable means independently of the further operation of said second handle.

10. A door lock including an outside handle pivotally supported for swinging movement into and out of a recess in the outer side of a door to which said lock is applied, an inside handle, means operated by said inside handle for swinging said outside handle into said recess, and means operating independently of said inside handle and said means operated thereby, normally tending to project said outside handle from said recess.

11. A door lock including an outside handle pivotally supported for swinging movement into and out of a recess in the outer side of a door to which said lock is applied, an inside handle, means operated by said inside handle for swinging said outside handle into said recess, yieldable means operating independently of said inside handle and said means operated thereby, for projecting said outside handle from said recess, and means released by the operation of said inside handle for locking said outside handle in retracted position, against the action of said yieldable means.

12. The combination with a door having a recess in its outer side and provided with vertical ways for a glass panel in its interior; of a lock for said door including a latch bolt within said door, an outside handle pivotally supported for swinging movement into and out of said recess, an inside handle, and means for retracting said latch bolt by a rotative movement of said inside handle and swinging movement of said outside handle, said means including a rocker and

links for converting the rotary motion of said inside handle to swing said outside handle.

13. A door lock having a latch bolt, an outer and an inner handle, said outer handle being adapted for movement into operative and inoperative position, spring means for urging said handle into operative position, said latch bolt being adapted for withdrawal by both handles, said inner handle being adapted when moved from a given point in one direction to release the outer handle from inoperative position to operative position and to withdraw the latch bolt, and when moved from the given point in the opposite direction to withdraw the outer handle from operative to inoperative position. 15

14. In combination with the outer handle of a lock for doors of vehicles, means projecting within the vehicle for retracting the outer handle, said outer handle also being adapted to be retracted manually from the outside of the vehicle, means for retaining said outer handle in retracted position, means for projecting said outer handle, and means operable both from within and without the vehicle for releasing said handle for projection by said projecting means. 25

15. In a lock mechanism for a door having a depression formed in one side face thereof, said lock mechanism comprising a handle operatively connected to the lock mechanism, said handle having a portion projecting through an aperture in said door face to permit the handle to be moved between a projected position and a retracted position occupying said depression, a second handle mounted on the other side of the door for movement in opposite directions from a normal position, means connecting the second handle to the locking mechanism to effect operation of said mechanism by movement of the handle in one direction, and means for effecting movement of the first handle between said two positions controlled by movement of the second handle in the opposite direction. 35

16. In a lock mechanism for a door having a depression formed in one side face thereof, said lock mechanism comprising a handle operatively connected to the lock mechanism, said handle having a portion projecting through an aperture in said door face to permit the handle to be moved between a projected position and a retracted position occupying said depression, spring means for projecting the handle, and means controlled from a remote point located out of axial alignment with the handle for retracting the handle into said depression and retaining it therein. 45

17. In a lock mechanism for a door having a depression formed in one side face thereof, said lock mechanism comprising a handle operatively connected to the lock mechanism, said handle having a portion projecting through an aperture in said door face to permit the handle to be moved between a projected position and a retracted position occupying said depression, spring means for projecting the handle, a second handle rotatably mounted on the other side of the door, and a link and lever system connecting said handles to cause rotation of said second handle to effect retraction of the first handle into the depression. 60
